(57) **CLAIM**

The ornamental design for a thematic handle extension for wheeled device, as shown and described.

DESCRIPTION

FIG. 1 is a front right perspective view of a thematic handle extension for wheeled device showing our new design; FIG. 2 is a back left side perspective view of the thematic handle extension for wheeled device in FIG. 1.

FIG. 3 is top view of the thematic handle extension for wheeled device in FIG. 1.

FIG. 4 is a bottom view of the thematic handle extension for wheeled device in FIG. 1.

FIG. 5 is a left side view of the thematic handle extension for wheeled device in FIG. 1.

FIG. 6 is a right side view of the thematic handle extension for wheeled device in FIG. 1.

FIG. 7 is a front view of the thematic handle extension for wheeled device in FIG. 1.

FIG. 8 is a back view of the thematic handle extension for wheeled device in FIG. 1; and,

FIG. 9 is a left side view of the thematic handle extension for wheeled device in FIG. 1, with the handle rotated forward ninety degrees.

The broken lines shown in FIGS. 1-9 depict environmental and unclaimed subject matter.
